CLAIM

What is claimed is the ornamental design for a bumper for vehicle, as shown and described.

DESCRIPTION

FIG. 1 is a top, front, and left side perspective view of a front bumper for vehicle showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the figures depict portions of the bumper for vehicle that form no part of the claimed design.
